UNITED STATES PATENT OFFICE.

MILTON A. HAMILTON, OF DETROIT, MICHIGAN.

KNOCKDOWN BOX.

SPECIFICATION forming part of Letters Patent No. 373,828, dated November 29, 1887.

Application filed March 7, 1887. Serial No. 230,022. (No model.)

To all whom it may concern:

Be it known that I, MILTON A. HAMILTON, of Detroit, county of Wayne, State of Michigan, have invented a new and useful Improvement 5 in Knockdown Boxes; and I declare the following to be a full, clear, and exact description of the same, such as will enable others skilled in the art to which it pertains to make and use it, reference being had to the accompanying drawings, which form a part of this specification.

My invention has for its object the construction of a novel box for shipping and other purposes, constructed in whole or in part of a fabric formed of a series of slats interwoven with a series of wires, said box being readily reducible to a knocked-down condition for transportation or storage, or for the return of the same to the shipper; and it consists of the 15 combinations of devices and appliances hereinafter specified, and more particularly pointed out in the claims.

In the drawings forming part of this specification, Figure 1 represents a closed box embodying my invention. Fig. 2 is an additional view of the same opened out into knocked-down condition. Fig. 3 is a cross-section illustrating how the ends or partitions may be engaged with the sides of the box. Fig. 4 is a 20 separate view of a portion of fabric entering into the construction of the box where ventilation is desired. Fig. 5 is a separate view of one of the channel-cleats. Fig. 6 illustrates a modification in which the slats constituting 25 the sides extend perpendicular to the plane of the bottom. Fig. 7 is a separate view showing the slats notched on the edge to receive the wire. Fig. 8 is a separate view showing a croze-channel of wire. Fig. 9 is a modification showing a single wire engaging a head. 30

I carry out my invention as follows:

A represents the fabric entering into the construction of the box, said fabric constructed of a series of wooden slats, *a*, preferably 35 laid side by side or edge to edge, said slats constituting the woof of the fabric, the warp consisting of a series of wires, *a'*. A fabric so constructed is strong, and, as will be seen, is readily flexed at any point without 40 materially weakening the structure. This fabric I have found adapted in any convenient

way in the construction of boxes for the shipment of fruits and other articles.

B represents channel-cleats, which may be fastened at one end of a series of slats, said 55 cleats adapted, when the fabric is folded, to engage in their respective channels analogous sections which may constitute the ends or intermediate partitions of the box. Thus the channel-cleats may be attached to the sides 60 *A' A²*, the bottom *A³* of the box, and to the cover *A⁴* of the case. These channel-cleats are constructed of separate pieces of wood grooved, as shown, to form a groove or croze to receive 65 an edge of the end pieces or partition, said cleats being fastened in any suitable manner to the slats of which the fabric is composed—as, for instance, by tacks or nails. These channel-cleats are permanently engaged with the fabric and remain engaged therewith when the 70 package is knocked down and are in place to engage the edges of the end pieces or partitions in making up a package. Two or more of these channel-cleats may be employed to engage said end pieces or partitions. When 75 so constructed, the channels of said cleats will obviously inclose the four edges of the ends *C* when the box is closed. These ends may be constructed of the foregoing fabric or they may be of one or more pieces of boards, while the 80 remaining four sides of the box may be made of said fabric.

When it is designed to provide the box with a partition, additional channel-cleats may be provided and suitably engaged to embrace the 85 ends of said partitions, the partitions themselves either being made of the fabric or of boards, as may be preferred. When the front, rear, and bottom have thus been brought into position to embrace the edges of said ends 90 within the channels of said cleats, they may be fastened in such position by brads or tacks or by wire—as, for instance, at the corners.

It is obvious that the lid may be closed down upon the upper edges of the ends in an analogous manner, in which position it may be fastened securely by wires *D*, as shown in Fig. 1.

When this fastening is undone, the lid may be opened, the wire of the fabric serving the purpose of a hinge—*i. e.*, permitting the cover 100 to flex at the division-line between it and the side.

It will furthermore be seen that the front, bottom, rear, and top may be made of an integral piece of fabric. The lid may be thus engaged upon one of the four sides of the box, 5 as may be preferred, without any alteration in the usual construction.

It is evident that a box so made is neat and inexpensive. Not only may it readily be knocked down, as above described, but it may 10 with equal facility be made up again into a complete box for use. When knocked down it is in a very compact shape, occupying very little room. No nails are used in the ordinary manner, a few brads or tacks sufficing all purposes. When the channels have once been engaged with the fabric, as already set forth, no further tacks, brads, or nails are required in 15 assembling the parts for use, except possibly at the corners. A box so constructed may be 20 used again and again without injury.

I prefer to make the fabric of ordinary lath, either plain or rough, with the wires with which it is interwoven.

It will be evident that should any single 25 slat become broken it will not materially injure the safety of the package.

A box so constructed is very much lighter than a box constructed in the ordinary manner, while it possesses all the necessary 30 strength possessed by ordinary board boxes made of much thicker material.

Instead of having the slats arranged in the manner shown in Fig. 1 of the drawings, the slats constituting the sides may be arranged to 35 stand perpendicular to the bottom of the box.

When it is desired to make a tight box, a box so constructed as now described may be lined with any suitable fabric, a^2 , as illustrated in Fig. 2.

40 When it is desired to bring the edges of the slats in close proximity where hard wood is employed, it may be desirable to provide the said slats upon the edges with notches a^3 , as shown in Fig. 7, to receive the wire. Where 45 soft wood is employed, the wire may be embedded in the wood sufficient to answer this purpose. When this fabric is employed in the construction of boxes or crates requiring ventilation, the slats may be interwoven with the 50 wire, separated a desired distance from each other, as shown in Fig. 4.

For many purposes the fabric may be woven 55 in such a manner as to have the wires at the sides or ends of the box or at intermediate points project out from the face of the slats upon the surface used for the inside of the box, as shown in Fig. 8 at a^5 and a^6 , two lines of such projected wires forming a channel for the reception of the ends or other desired parts.

60 When thus constructed, a few nails may be used at about the center of the sides to more firmly engage the sides with the ends at these

points. In such cases the channel-cleats, as shown in Fig. 2, may be dispensed with.

Instead of projecting two adjacent wires to 65 form a croze-channel, as shown in Fig. 8, a single wire entering into the construction of the fabric may be projected from the face of the slats, as shown in Fig. 9 at a^7 , the adjacent partition, end, or side, as the case may be, being recessed, as shown at e , to receive the projected wire and form the required engagement.

What I claim is—

1. A box in which the four sides are made of a fabric of slats interwoven with a warp of 75 wires, having in combination therewith end pieces, said fabric provided with channel-cleats B, fastened to said slats for receiving the edges of said end pieces, respectively, substantially as described.

2. A box in which the sides and ends are made of a fabric consisting of slats woven together with a warp of wire, said fabric provided with channel-cleats B, attached to said slats for receiving the edges of the end pieces, 85 substantially as described.

3. A fabric for the construction of packages, consisting of wooden slats interwoven with a warp of wires and having in combination therewith 90 separate channel-cleats B, permanently fastened to said slats, substantially as and for the purpose described.

4. A box in which the sides and ends are made of a fabric of slats interwoven with a warp of wires, said sides formed of a single 95 integral piece of said fabric and provided with croze-channels adapted to engage said ends, substantially as described.

5. A package in which the sides or sides and ends are formed of a fabric of wooden 100 slats interwoven with a warp of wires, said slats notched upon their edges to receive said wires and bring the adjacent edges of the slats tight together, substantially as described.

6. A fabric for the construction of a box or 105 package, consisting of wooden slats interwoven with a warp of wires, said slats notched upon their edges to receive said wires and bring the adjacent edges of the slats tight together, substantially as described.

7. A package consisting of wooden slats interwoven with a warp of wires, the wire of 115 said fabric projected upon one of the faces at desired points, and having in combination therewith recessed ends or partitions engaging said projected wires, substantially as described.

In testimony whereof I sign this specification in the presence of two witnesses.

MILTON A. HAMILTON.
